UNITED STATES PATENT OFFICE.

FRANCIS W. MORRIS AND MICHAEL C. NILAND, OF LOCKPORT, NEW YORK.

EXTERIOR LIGHTING SYSTEM FOR RAILROAD TRAINS.

Application filed August 31, 1923. Serial No. 660,432.

To all whom it may concern:

Be it known that FRANCIS W. MORRIS and MICHAEL C. NILAND, both citizens of the United States, and residents of Lockport, in

5 the county of Niagara and State of New York, have invented certain new and useful Improvements in Exterior Lighting Systems for Railroad Trains, of which the following is a specification.

10 This invention contemplates the provision of light projecting means designed to be attached preferably to the locomotive end of a railway train to establish a light zone extending on either or both sides of the train 15 from the locomotive to the opposite end and serving to clearly illuminate the exterior portion of the train traversed thereby, as well as the adjacent road bed. Preferably, the projecting means is mounted for movement to various positions of adjustment; thereby enabling the light rays to be diverted from normal position and directed either laterally or in the opposite longitudinal direction of the train.

25 The important objects of the invention are to render possible detection of any person or object, entering or leaving any part or portion of the train; thereby reducing the chances of successful robberies, train 30 hold-ups, and the like; to minimize the danger of accidents at unguarded railway crossings; to facilitate proper reading and understanding of any signal or signals; to facilitate the detection of smoking or blazing journal boxes; to prevent rear end collisions; to enable rapid backing of a train at night with a greater degree of safety; to lessen the number of employees required for the safe operation of the train, and to permit elimination of the two tail lights ordinarily carried by the trains.

Other objects and advantages of the invention, not specifically stated above, will become apparent from the following detailed description and accompanying drawings; wherein—

Fig. 1 is a view in side elevation of a train equipped with our invention.

Fig. 2 is a view in rear elevation of a locomotive tender showing the manner in which the light projecting lamps are fixed to the grip handles of the tender.

Fig. 3 is a side elevation of one of the eliminating units as viewed in normal position.

Fig. 4 is a view in rear elevation of one of the eliminating units.

Fig. 5 is a top plan view of the said eliminating units.

Fig. 6 is a sectional view on the line 6—6 60 of Fig. 5.

In Fig. 1 of the drawing, we have shown a portion of a railway train consisting of a locomotive 5, locomotive tender 6, and one or more freight or passenger cars 7. At the 65 rear end the tender 6 is provided with the usual grip handles 8 arranged on opposite sides thereof.

In accordance with the present invention, each grip handle 8 is utilized to support one 70 or more lamps 9 constructed as hereinafter described or in any other suitable manner. As shown to advantage in Fig. 1, these lamps are normally arranged to direct the light rays rearwardly at each side of the 75 train to illuminate the exterior portions of the car or cars 7 as well as the adjacent road bed. In this way a zone of light is established at each side of the train extending from the tender 6 preferably to the opposite end of the train and serving to facilitate 80 the detection of any person or object entering or leaving the train at any point, the reading and proper understanding of signals between members of the train crew; the prompt detection of smoking or blazing journal boxes, etc.

While the lamps 9 are herein shown as attached to the tender 6, it is to be understood that they may be positioned on the 90 locomotive 5 or any car or cars 7 or the caboose or at any other point consistent with the purposes of the invention. Also these lamps may be in any desired number and positioned to illuminate not only the sides, but the top, bottom and all other exterior portions of the car or cars along which the light rays are directed.

As herein shown, each lamp 9 comprises an outer casing 10 of tubular form in which is arranged a correspondingly shaped reflector casing 11. Lamps 12 and 13, carried by the inner closed end of casing 10 extend forwardly into the corresponding end of the reflector casing 11 through suitable openings 14 and 15 provided for this purpose, either or both the lamps 12 and 13 to be of a red or any other suitable color. Surrounding the open end of the reflector casing 11 is an integral annulus 16 made slightly 110

curved or concave to afford the desired strength and rigidity and serving to hold the casings 10 and 11 in the desired spaced relation. Inwardly of the annulus 16, casing 11 is provided with an annular seat or rib 17 to which a lens 18 is held by means of a clamping ring 19 threadedly engaged with the open end of the casing. The outer end of casing 10 is closed in a similar manner 10 by a lens 20 confined between the threaded ring 21 and a central aperture cap member 22.

In practice it has been found that the reflector lens 18 may be conveniently dispensed with in certain instances. However, when two lenses are used, as herein shown, the same should preferably be of the plano-convex type and of suitable focal length arranged with the convex surfaces opposing 20 one another and spaced apart a distance approximately equal to one-fourth of the diameter of the lenses. This specific structure and arrangement of the lenses while giving unexpectedly good results in the projection 25 of the light rays is not, however, absolutely essential, as lenses of other types can be used to advantage and may be spaced apart in any manner conducive to the attainment of the best results in the projection of the light rays 30 passing therethrough.

While any suitable means may be provided for holding the lamps 9 to the grip handles 8, we prefer to use, for this purpose, the particular form of bracket disclosed to 35 advantage in Figs. 3 to 6, inclusive. As herein shown, the said bracket consists of a pair of complementary clamp members 23 and 24 held to opposite sides of one of the grip members 8 by means of the bolts 25. The 40 inner opposing surfaces of these clamp members are recessed as at 26 to conjointly provide an opening conforming to the cross sectional contour of the grip member 8 and receiving the latter therethrough. At one 45 end the members 23 and 24 are interlocked by means of a projection 26' on one member fitting in a correspondingly shaped slot 27 formed in the other member for this purpose, said projection and slot being inclined 50 with respect to the inner longitudinal faces of the clamp members to cooperate with the bolts 25 in preventing relative longitudinal movement of the parts. Adjacent the interlocked extremities, the inner faces of members 23 and 24 are recessed to conjointly provide a vertical slot 26. The members 23 and 24 are further recessed to provide upper and lower horizontal slots 27 extending the full width of said members and intersecting the vertical slot 26. The lamp carrying part of the bracket comprises an approximately L-shaped member presenting a vertical arm 28 and a horizontal arm 29. The lamp 9 is mounted on the horizontal arm 60 29 and is secured thereto by a bolt 30 pass-

ing upwardly through said arm and through the casing 10 of the lamp, pivotal movement of the lamp with or about the bolt 30 being prevented by a suitable arrangement of braces 31 connected between the casing 10 and the vertical arm 28. The latter arm is provided with upper and lower spaced extensions 32 normally arranged to extend transversely through the aforementioned slots 27 of the members 23 and 24. The extensions 32 are provided with vertical slots 33, closed at each end and registering with aligned portions of the vertical slots 26 to provide for the positioning of the securing bolt 34. A second securing bolt 35 is positioned to extend vertically through the slots 33 between the outer closed ends of these slots and the adjacent side of the clamp members 23 and 24, the purpose of this bolt being to prevent pivotal movement 85 of the extensions 32 about the bolt 34.

Normally, each illuminating unit is arranged as shown in Figs. 1 and 2 with the clamp members 23 and 24 extending laterally from the grip member 8 and the lamp 9 and its supporting arm 29 directed rearwardly. However, on referring to Fig. 5, it will be apparent that by removing the bolt 35, the lamp 9 and its supporting arm 29 may be positioned at the opposite sides of the clamp members 23 and 24 or may be disposed in longitudinal alignment therewith. When the lamp 9 is aligned with the clamp members 23 and 24 it will be understood that the extensions 32 of the arm 28 will extend longitudinally of the slots 27, to permit the bolt 35 to be replaced by passing the same vertically through the inner aligned ends of the slots 26 and 27. From this, it will be apparent that our improved lighting means while normally arranged to create a light zone extending on opposite sides of the train from the locomotive to the opposite end is capable of being diverted from normal position to direct the light rays either laterally or forwardly of the train should such adjustment become necessary for any reason.

The tender 6 is provided with the usual wiring system 36 from which current is conducted to the lamps 9 through suitable conductor leads 37 passing through insulating sleeves 38 carried by the lamp brackets.

While in the foregoing, we have described what we now consider to be the preferred embodiment of the invention, we do not wish to be limited to the exact details of construction and arrangement of parts herein set forth but reserve the right to resort to such changes as may later prove desirable, provided of course, that the contemplated changes come within the scope and spirit of the appended claims.

What we claim is:

1. Means for illuminating the exterior of

5 railroad trains comprising, in combination with the grip handle of a locomotive tender, a pair of members formed to clamp the grip handle therebetween, means securing said members together in clamping engagement with the grip handle, a horizontally disposed lamp support adjustably connected to said members by a vertical pivot permitting adjustment of the support in a horizontal 10 plane, and a horizontally disposed projector lamp carried by the support and adjustable therewith to direct the light rays longitudinally or laterally of the tender.

15 2. The combination of a support including a horizontal member and a vertical member at one end of the horizontal member, a horizontally disposed projector lamp arranged on the horizontal member, a fastening screw passing through the horizontal 20 member and the engaging portion of the lamp and a plurality of braces connected between the lamp and the vertical member and serving to prevent pivotal movement of the lamp with or about said screw.

25 3. The combination of a projector lamp, a bracket comprising a movable member carrying said lamp and a stationary member adapted to be secured to a suitable support, upper and lower tongues projecting from the 30 lamp carrying member and formed with vertically aligned longitudinally extending slots, upper, lower and intermediate tongues projecting from the stationary member and also formed with vertically aligned longitudinally extending slots, said members being capable of assembly to extend either in alignment or at right angles to each other with the tongues of the two members disposed in interfitting engagement, the tongues 35 and tongue slots of the lamp carrying member being of greater length than the width of the tongues of the stationary member to project beyond one side of the latter tongues when the members are disposed at right 40 angles, and a pair of securing bolts adapted to be passed through the slots of both sets of tongues when the members are disposed in alignment, one of said bolts being removable to permit pivotal movement of the lamp carrying member about the remaining bolt to dispose the members in right angular 45 positions with the tongue slots of the lamp carrying member projecting beyond one side of the tongues of the stationary member to

50 permit the removable bolt to be reinserted in the projecting portions of the slots.

55 4. A projector lamp support comprising a movable lamp carrying member provided with projecting slotted tongues, a stationary member provided with projecting slotted tongues arranged for interfitting engagement with said first mentioned tongues, the two sets of tongues being capable of selective assembly to extend either in alignment or at right angles with respect to one another, the 60 tongues and slots of the lamp carrying member being of a length greater than the width of the tongues of the stationary member to project beyond side of the latter tongues when the two sets of tongues are disposed at right angles, and a pair of fastening bolts 65 adapted to be passed through the slots of both sets of tongues when the latter are in alignment, one of the bolts being removable to permit pivotal adjustment of the lamp carrying member to dispose the tongues thereof at right angles to the tongues of the stationary member, said removed bolt being then reinsertable in the slots of the lamp carrying member to occupy a position between the projecting ends of the slots and the adjacent side of the tongues of the stationary member.

70 5. A projector lamp bracket embodying a pair of complementary clamp members having the inner opposing surfaces thereof recessed adjacent one end to conjointly provide an opening conforming to the cross sectional contour of a supporting member received between said clamp members, an interlocking connection between the clamp members at the opposite end comprising a projection on one member fitting in a correspondingly shaped slot formed in the other member, and fastening bolts securing the 75 clamp members together and passing therethrough at opposite sides of the recesses.

80 6. A device according to claim 5, wherein the projection and slot interlocking the clamp members at one end are inclined with respect to the inner longitudinal faces of the clamp members to cooperate with the bolts in preventing relative longitudinal movement of the members.

85 In testimony whereof we hereunto affix 105 our signatures.

FRANCIS W. MORRIS.
MICHAEL C. NILAND.
